CLASP DEVICE

Richard G. Gloss, Cranston, R. I.

Application August 11, 1951, Serial No. 241,441

4 Claims. (Cl. 24—248)

1

This invention relates to a clasp or clasp finding and more particularly to the mechanical mechanism for retaining the clasp in certain positions.

One of the objects of this invention is to provide a clasp which may be frictionally retained in different positions to which it is set.

Another object of the invention is to provide a clasp which is frictionally maintained in position but will resist movement of a gripping jaw in one direction more than in the other direction.

Another object of the invention is to provide a clasp which is of simple construction and yet effective in its operation.

Another object of the invention is to provide a clasp which is so constructed that it may be soldered in one position without destroying the temper of the resilient part of the clasp.

With these and other objects in view, the invention consists of certain novel features of construction, as will be more fully described and particularly pointed out in the appended claims.

In the accompanying drawings:

Figure 1 is a perspective view of the clasp shown as secured to an ornamental part with which the finding cooperates;

Figure 2 is a sectional view on line 2—2 of Figure 1; and

Figure 3 is an exploded view of the different parts of the finding.

In proceeding with this invention I bend up into U-form a member having a pair of ears which are so spaced that they will receive the other part of the finding with which they are assembled. The other part of the finding comprises a pin with trunnions, one of which is out-of-round to fit into a corresponding out-of-round opening in one of the ears to prevent rotation of the pin. About the pin there is rolled an eye which is formed integral with the jaw which may be moved frictionally about the pin to hold it in different positions.

With reference to the drawings, 10 designates a member having a base portion 11 which may be soldered to an ornament 12, which in turn will act as one of the gripping jaws of the completed device. From this base 11 there extends ears 14 and 15 which are enlarged at their ends as at 16 and 17. A cylindrical hole 18 is formed in the ear 14 and an elongated slot 19 is formed in the ear 15. When soldered in position, these ears are left spread apart sufficiently so that a pin may be assembled between them.

A jaw designated generally 20 has an eye 21 rolled from the stock of the jaw, which eye is

substantially cylindrical. Its edge 22 closely approaches the body portion 23 of the jaw but may be spaced slightly therefrom.

A pin 24 is formed cylindrical and has trunnions extending from its opposite ends. One trunnion 25 is circular in cross section and may have a bearing in the opening 18 in ear 14. The other trunnion 26 is out-of-round or of elongated formation, such as rectangular in cross-section and is of such shape as to fit into the slot 19 in the ear 15. The diameter of the pin 24 is slightly larger than the inner diameter 27 of the eye 21 and for assembly purposes this pin is forced into the eye 21 so as to expand this eye. There is sufficient inherent resiliency in the stock so that there is always a tendency for the eye 21 to contract and grip the pin 24. As these parts are substantially cylindrical and not in any way flattened or off-set, there will be at least a three-point bearing engagement between the eye 21 and the pin 24 so as to provide an extended frictional surface.

With the pin assembled in the eye 21 and the ears spread apart a distance to receive the pin after the base 11 is soldered to the ornament 12, the pin and jaw are placed between the ears and the ears then bent into position so that the pin is held between the ears in a non-rotatable manner.

30 By rolling the eye 21 counter-clockwise as shown in Figure 2, a movement of the jaw 30 in the direction of the arrow 30, as shown in Figure 2, will tend to close or contract the eye 21 and thus cause it to more securely grip the pin 24 35 while frictioning thereon, while a movement in the opposite direction would tend to expand or enlarge the eye. Thus, an opening movement of the jaw will apply a greater friction and cause more pressure to be exerted for opening the jaw than moving the jaw in the opposite direction toward gripping position. This is of importance 40 as a tendency to resist opening of the jaw will maintain the jaw in gripping position which is desired.

45 I claim:

1. In a clasp device a member having a pair of ears having bearing openings therethrough, a cylindrical pin received in said openings and extending between said ears, means to prevent the pin from rotating relative to said member, a jaw having a generally cylindrical resilient eye engaging said pin with an inherent tendency to contract and friction against said pin, said eye being coiled in a direction of rotation for closing 55 movement of the jaw with a normal diameter

smaller than the pin so as to grip the pin whereby to tend to cause contracting of the eye upon opening movement of the jaw and expanding of the eye upon closing movement of the jaw.

2. In a clasp device as in claim 1 wherein the pin has trunnions extending into said ears, one of which trunnions is out-of-round to prevent turning of the pin in the ears.

3. In a clasp device as in claim 1 wherein the member is adapted to be secured to an ornament which will serve as a second jaw of the clasp.

4. In a clasp device as in claim 1 wherein the member is fixed to an ornament.

RICHARD G. GLOSS.
